EMIEL R. FOX, OF OAKWOOD, NEW YORK

LOCK

Application filed May 18, 1928. Serial No. 278,665.

My invention has reference to locks and more particularly locks used on trunks, luggage and similar articles.

The object of my invention is to produce a lock which locks automatically and always remains in locked condition until opened by a key, and the lock is so constructed and designed that upon the withdrawal of the key, the lock automatically closes again.

10 In the annexed drawing in which I have shown, by way of illustration, an embodiment of my lock, Fig. 1 is a side elevation showing a portion of the casing broken out, while Fig. 2 is a section along line II—II in Fig. 1.

15 1 is the casing and 2 the rotatable barrel extending into the casing and adapted to receive the key indicated at 3.

At its inner end, the barrel is provided with a double cam indicated at 4 provided with the 20 two raised faces shown in Fig. 2 at 5 and 6.

At 7 and 8 in Fig. 2 are shown the two locking bolts adapted to engage and enter into two apertured members 9 and 10 respectively, provided on a lug, or lugs, (not shown) and 25 adapted to enter the casing 1 through slots 11 and 12 respectively.

The locking bolts 7 and 8 are each provided with a part extended at right angles from said locking bolts and respectively designated, 13 30 and 14. These parts, as will be seen from Figs. 1 and 2 of the drawing, when the locking bolts are in locking position bear against the lower portions of cam 4 and they are held in this position respectively by springs 15 and 35 16 fastened to partition walls 17 and 18, respectively inside casing 1.

At 19 is shown a guide for the locking bolts 7 and 8.

If by the key 3 shown in Fig. 1 being inserted in the barrel 2, the barrel and thereby the cam 4 is turned in the direction indicated by the arrow, the two locking bolts by means of the raised portions 5 and 6 of the cam engaging the portions 13 and 14 will be pushed against the action of the springs 15 and 16 in the direction of the small arrows shown in Figs. 1 and 2, thereby releasing the apertured members 9 and 10 which now can be pulled out of the casing through the slots 11 and 12.

50 As soon as the pressure on the key is re-

leased, the springs 15 and 16 will immediately move the locking bolts 7 and 8 back into the positions shown in Figs. 1 and 2, at the same time moving the cam back to the position also shown in the drawing.

55

As shown in Fig. 2 at 20 and 21 respectively, the ends of the locking bolts are so shaped that upon the members 9 and 10 being pressed into the casing through the slots 11 and 12, they will force the bolts back sufficiently to 60 allow the two members 9 and 10 to be pressed entirely into the casing to be engaged by the locking bolts as shown in the drawing.

The members 9 and 10, where the lock is used on a trunk, are supposed to be fastened to or be formed integral with a hinged member secured to the lid of the trunk. Of course, each member 9 and 10 can be separately hinged to the lid.

65 While I have shown an embodiment of my invention, I do not, of course, limit myself to the exact construction, because various details therein may be modified without a departure from my invention.

70 I claim:

A lock of the type described, comprising a casing having slots adapted to admit members to be held in a locked position therein, partitions in said casing sliding bolts disposed in said casing so as to engage said members, 75 and each of said bolts having an arm extending at right angles, guiding means for said bolts, leaf springs secured to said partitions adapted to normally hold said bolts in engaging position, said leaf springs being of U- 80 shape with one of the legs secured to said partition and the free legs thereof positioned in normal abutting relation to said arms upon said bolts, and a cylindrical barrel rotatably mounted in said casing, and having a double 85 acting cam portion, said barrel being adapted to be rotated by a key inserted therein to simultaneously move said sliding bolts out of their engaging position by the pressure exerted by said cam portion on said arms.

75

90 In testimony whereof I affix my signature.
EMIEL R. FOX.
